(57) **CLAIM**

The ornamental design for a telescope mounting receiver for firearms, as shown and described.

DESCRIPTION

FIG. 1 is an isometric illustration of the telescope mounting receiver for firearms of our ornamental design, showing bottom, side and one end the design;

FIG. 2 is another isometric illustration of the telescope mounting receiver for firearms of our ornamental design, showing top, opposite side and opposite end of the design as compared with FIG. 1.

FIG. 3 is a side elevational view of the telescope mounting receiver for firearms of our ornamental design;

FIG. 4 is a side elevational view of the telescope mounting receiver for firearms of our ornamental design, showing the opposite side elevational view as compared to that shown in FIG. 3;

FIG. 5 is a top plan view of the telescope mounting receiver for firearms of the design;

FIG. 6 is a bottom view of the design;

FIG. 7 is a front view of the telescope mounting receiver for firearms of our ornamental design; and,

FIG. 8 is a rear view of the telescope mounting receiver for firearms of the design.
